UNITED STATES PATENT OFFICE.

JOHN B. FLETCHER, OF NEWPORT, KENTUCKY.

RECIPROCATING WATER-MOTOR.

1,118,852.

Specification of Letters Patent.

Patented Nov. 24, 1914.

Application filed November 29, 1912. Serial No. 734,115.

To all whom it may concern:

Be it known that I, JOHN B. FLETCHER, a citizen of the United States, residing at Newport, in the county of Campbell and State of Kentucky, have invented certain new and useful Improvements in Reciprocating Water-Motors, of which the following is a specification.

My invention relates to an improved water motor.

One of the objects of the invention is to produce a very simple, cheap and durable type of a reciprocating water motor of the general character commonly used for energizing a washing machine.

Another object of the invention is to provide an improved mechanism for unseating, shifting and reseating the valves.

The specific character of the improvement will be pointed out in connection with the description of the accompanying drawings, forming a part of this specification, in which:—

Figure 1 is a central vertical longitudinal section through the motor. Fig. 2 is a view, partly in section, showing one end of the motor with the piston and valves and valve actuating spring, shown in their relative positions for operation. Fig. 3 is a section on line $x-x$ Fig. 1. Fig. 4 is a section on line $y-y$ Fig. 1.

The motor comprises the hollow cylinder 1, with the inclosing heads 2.

3 represents the piston formed with the non-communicating supply chamber 4 and exhaust chamber 5. The right hand face of the piston is connected to the piston rod 6, passing through the head 2 and stuffing-box 7. The left hand face of the piston is connected to the parallel hollow supply and exhaust rods 8, 9, which pass through the left hand head 2, and a suitable stuffing-box, it being understood that these hollow rods during their reciprocation telescopically engage the initial water supply and exhaust pipes.

11 represents a double inlet or supply valve in the supply piston chamber 4, adapted to alternately engage the seats 12, 13, of the inlet ports; the stem 14 of said valve passes through the opposite walls of the piston and on its outer ends there are formed the stub stems 15, 15'.

16 represents the stem of the exhaust valve in chamber 5, carrying the exhaust valve heads 17 disposed upon the outer faces of

the piston in position to coöperate with the piston exhaust valve seats 18, 19, of the outlet ports, the stub stems 20, 20', projecting outwardly beyond said heads.

21 represents a plate or valve stem connector loosely mounted on piston rod 6, having yoke ends 22 loosely engaging the stub stems 15, 20.

23 represents a plate or valve stem connector loosely mounted on the hollow rods 8, 9, and having the yoke ends 24 loosely engaging the stub stems 15', 20'.

25 represents a cylindrical coil spring loosely mounted on the piston rod 6 and positioned between the plate 21 and the right hand cylinder head. On each of the hollow rods 8, 9, is loosely mounted a cylindrical coil spring 26 positioned between the plate 23 and left hand cylinder head. It is the essential function of these springs to unseat, shift and reseat the valves and to insure this end, the cylinder heads are preferably formed on their inner faces with the pocket 27, into which the springs are solidly compressed, and the pockets 28, forming clearance spaces, to prevent the valve stems from contacting the cylinder head at the times the springs are solidly compressed. The loose connection between said plates and the stub stem produces a novel and useful function in the valve actuation which will be obvious from the disclosure of the operation.

Assuming the parts in the position shown in Fig. 1, the water will be flowing into the supply chamber 4, from the left hand end, and the water will be exhausting out of the right hand end of the cylinder, through the chamber 5, the piston moving toward the right hand end of the cylinder. The spring 25 will be moved by a plate 21, into the pocket 27, and solidly compressed, as shown in Fig. 2, at which time there is an appreciable clearance space between the ends of the valve stems and the right hand cylinder head.

The further urging of the piston will unseat the valves and the reaction of the spring will shift the valves toward their opposite seats, the valves moving as a unit during this unseating and shifting because of the plate connection, but in the reseating of the valves, the loose connection between the stub stems and plate becomes effective and enables a slight independent movement of the supply and exhaust valves, whereby they are independently reseated, whereupon

the valves being reversed, the water flow is reversed, and the piston moves to the left hand end of the cylinder, where this action is repeated when the springs 26 become 5 solidly compressed.

It has been found from experience that where the valves are rigidly connected the motor is practically inoperative for commercial usage, because it has been found 10 almost impossible to properly reseat the valves when they are entirely unitary in movement, and this difficulty becomes enhanced with the slightest wear of the valves or their seats.

15 With my improvement the valves move as a unit in their unseating and shifting operations, but have sufficient independent movement through their connecting medium to enable them to independently assume 20 their reseating or final movements.

By reason of this improvement a very simple and cheap motor is produced, without any rigid contact of the valve stems against the cylinder heads. The operation of the 25 motor is efficient and invariable, while at the same time a more durable motor is produced, as the valve final movements automatically accommodate themselves to the slight wear of the parts inherent in a continuous usage to which a motor of this character is subjected.

It will further be noted that the plates have no rigid or binding connection at any 35 point with the valve stub stems in a plane transverse to the longitudinal line of the valve movements. It results from this construction that the valves may be characterized as floating within the limitations of the plate connections. That is, they are free to 40 rotate on their axes or to move slightly in vertical plane. Therefore, there are no fixed or definite guides for concentrically alining the valve heads relative to their seats, but they automatically find their seats accurately and invariably under the influence of 45 the water pressures and flows as they are moved longitudinally under the spring influence, and the precision and reliability of the valve seating operations is not dependent upon concentric guides, which are never 50 unitarily accurate and which impair the efficiency of valve seating whenever the inevitable wear of parts occurs.

Having described my invention, I claim:—

55 1. In a reciprocating water motor, a cylinder, inclosing heads, a piston comprising non-communicating supply and exhaust chambers, hollow piston rods therefor, a double inlet valve in the supply chamber, a

double exhaust valve in the exhaust chamber, connectors on the piston rods loosely uniting said valve stems, causing the valves to move unitarily in unseating and shifting operations and enabling them to move independently in valve seating operations, 65 and cylindrical coiled springs operatively positioned between said connectors and cylinder heads, said springs having a tension always less than the force required to unseat the valves, whereby they compile coil 70 on coil forming a rigid abutment for unseating the valves.

2. In a reciprocating water motor, a cylinder, inclosing heads, a piston comprising non-communicating supply and exhaust 75 chambers, hollow piston rods therefor, a double inlet valve in the supply chamber, a double exhaust valve in the exhaust chamber, connectors on the piston rods loosely uniting the valve stems, causing them to 80 move unitarily in unseating and shifting operations and enabling them to move independently in the final or seating operations, said loose connections providing floating valves movable longitudinally with and relative to the connectors, and cylindrical coiled springs positioned between said plates and heads, said springs having a tension always less than the force required to unseat the valves, whereby they compile coil 85 on coil forming a rigid abutment for unseating the valves.

3. In a reciprocating water motor, a cylinder, inclosing heads, a piston comprising non-communicating supply and exhaust 95 chambers, hollow piston rods therefor, a double inlet valve in the supply chamber, a double exhaust valve in the exhaust chamber, said valves having stem projections beyond the piston faces, means connecting said stem projections upon each side of the piston, said means being adapted to move unitarily with the valves and being adapted to permit movements of the valves relative to said connecting means, and cylindrical coil 100 springs on the piston rods between said valve connecting means and the cylinder heads, said springs having a tension always less than the force required to unseat the valves, whereby they compile coil 105 on coil forming a rigid abutment for unseating the valves.

In testimony whereof, I have hereunto set my hand.

JOHN B. FLETCHER.
